UNITED STATES PATENT OFFICE.

PAUL SCHWIDEWSKI, OF BERLIN, GERMANY, ASSIGNOR TO THE FIRM OF
ARLT AND FRICKE, OF BERLIN, GERMANY.

HAIR-DRYING APPARATUS.

No. 841,584.

Specification of Letters Patent.

Patented Jan. 15, 1907.

Application filed November 20, 1905. Serial No. 288,326.

To all whom it may concern:

Be it known that I, PAUL SCHWIDEWSKI, tinker, a subject of the King of Prussia, German Emperor, residing at 9 Falkensteinstrasse, in the city of Berlin, Kingdom of Prussia, and German Empire, have invented a certain new and useful Hair-Drying Apparatus, of which the following is a specification.

This invention has reference to a hair-drying apparatus in which hot air is caused to flow, by means of a small fan-wheel, against the moist hair, which is dried in this manner.

The invention consists in the fact that the hair-drying apparatus is so arranged and constructed that it may be held with one hand while it is operated at the same time by the hand holding the apparatus, so that the person holding the apparatus is free to comb the hair with the other hand and is also able to direct the hot-air current toward the hair that has been combed through. An additional important improvement as compared with the hair-drying apparatuses now in use is presented by the fact that the gear-wheels for actuating the fan-wheel are not exposed to the action of the heating-flame, so that the gearing remains in working order during the life of the apparatus. Besides, the new hair-drying apparatus is constructed in such a manner as to yield a vigorous current of air without requiring much work.

Upon the accompanying drawings I have shown the new apparatus, by way of example, in two forms of construction.

Figures 1 and 2 illustrate the new hair-drying apparatus in side view and vertical section and in rear view, respectively; the part serving for the reception of the heating device serving at the same time as a handle in this modification. Figs. 3 and 4 show the actuating device in two working positions. Figs. 5 and 6 are representations of another form of construction of the apparatus where a separate handle is provided for holding the apparatus, Fig. 5 showing this form of apparatus in vertical section, and Fig. 6 in horizontal section through the casing inclosing the fan-wheel.

The hair-drying apparatus comprises a cone-shaped casing *a*, which is connected by a curved extension to the box-shaped casing *b*, inclosing the fan-wheel *c* and open at the front, so that the air-current produced by the

fan-wheel is forced out at the front side of the apparatus. The cone-shaped part of the casing *a* constitutes the handle of the apparatus and is provided at its lower end with perforations, holes, or the like, so that the air may enter therein, while it is closed at the bottom by a swinging cover *m*, upon which the spirit-lamp *l* is mounted.

The shaft *d* of the fan-wheel *c* is journaled at one end in the web *n* and at the other end in a shoulder *o* of the casing *a*, the end of the shaft projecting from the casing *a* being provided with a gear-wheel *p*, which transmits the rotating movement produced by the clockwork *r* to the fan-wheel *c*. This clockwork is actuated by an operating-lever *g*, which is placed so near the conical part of the casing *a*, constituting the handle, that it is possible to operate said lever with one finger of the hand holding the apparatus, while the backward movement of the lever is caused by the action of a spring. For this purpose the clockwork is provided with a ratchet-wheel *f*, with which the ratchet-pawl *i*, which is pivoted to the lever *g*, is made to engage, the pawl being influenced by the spring *k*.

When the lever *g* is forced backward in the direction of the arrow shown in the drawings by the thumb of the hand holding the casing *a*, the ratchet-wheel *f* is moved to a certain extent, since the ratchet-pawl *i* engages with the teeth of the said ratchet-wheel *f*. By means of the intermediate wheel constituting the clockwork this rotation is transmitted to the shaft *d* of the fan-wheel *c*, so that when the lever is moved, for instance, from the position shown in full lines into the position shown in dotted lines the wheel is making a full revolution. As soon as the thumb is then withdrawn the spring *k*, which has been charged by the previous movement of the lever, (see Fig. 4, dotted position,) pulls the lever *g* back into the position shown in full lines in Fig. 3, the ratchet-pawl sliding inoperatively past the teeth of the wheel *f* in the well-known manner, the said pawl after having assumed its position of rest reengaging the wheel *f*, so that the next movement of the lever *g* by means of the thumb causes a rotation of the ratchet-wheel *f*, and consequently, also, of the fan-wheel *d*. The air expelled by the rotation of the fan-wheel is replaced by the admission of fresh air entering through the holes which surround the spirit-

lamp. This air flows past the flame, cooling the handle forming part of the casing *a*, the air being then mixed with the gases of combustion of the spirit and being then forced 5 against the moist hair. In this form of construction the clockwork is not exposed to the action of the hot gases, while this is not the case with the shaft of the fan-wheel, and this 10 fact is liable to interfere with the promptness of operation. This inconvenience is avoided in the form of construction shown in Figs. 5 and 6, where the clockwork for actuating the fan-wheel is arranged horizontally 15 above the flame of the small spirit-lamp and being protected from the direct action of the heat by a screen or protecting-wall. In this modification the lower part of the casing *a* is cylindrically shaped, and it is connected, by means of a hinge or the like, with the closing- 20 cap constituting the foot *m* of the apparatus, so that the spirit-lamp may be exposed by inclining the apparatus for the purpose of igniting or of refilling the lamp *l*. The cylindrical part *a* of the casing serves for mounting 25 the box-shaped casing *b* of the fan-wheel; but it is separated from said box by a circular-shaped protecting-plate *t* in such a manner that the gases of combustion of the spirit and the aspirated air are deflected sidewise 30 and are admitted to the fan-wheel *c* at the outer extremities of its vanes only. The box *b* in the constructional modification herein described is closed at the top by a cover *u*, which is provided with vent-holes, and which 35 is separated from the interior of the box *b* by a likewise perforated partition, upon which is mounted or attached the clockwork operating and rotating the shaft *d* of the fan-wheel. The handle *s* is arranged sidewise of 40 the box *b* in this construction, and above the said handle the lever *g* is arranged, which projects through a suitable opening of the box-cover and which serves for the actuation of a ratchet-wheel constructed in the manner 45 already described or in any similar manner. In this modification the fan-wheel does not only aspirate the air of combustion, but it also aspirates fresh air at the same time

through the cover of the box *b*, the air being expelled through the nozzle *b'*, arranged side- 50 wise of the box. By this means the effect is produced that the fan-wheel is protected against excessive heating by the flame in its center part also, so that the shaft of the fan-wheel is also protected, the said parts being, 55 furthermore, kept cool by the fresh and consequently cool air which is constantly introduced from above, so that they are kept in constant working order. On the other hand, by means of the air being admitted by 60 separate sources the inconvenience is avoided of excessive heating of the air which is to be admitted to the hair, which would cause headache with sensitive persons.

In order to produce as vigorous and as 65 compact an action as possible of the current of air expelled from the fan-wheel, a partition or guide wall curved in the direction of the rotation of the fan-wheel is arranged in the nozzle *b'*, as shown in Fig. 6 of the draw- 70 ings.

What I claim, and desire to secure by Letters Patent of the United States, is—

1. A hair-drying apparatus comprising a fan-wheel, a casing therefor means for rotating 75 said wheel, a burner connected with the fan-casing, a handle for the apparatus and a controlling-lever for the operating means located adjacent said handle so that said lever may be operated by the same hand which 80 holds the handle.

2. A hair-drying apparatus comprising a casing having its lower part of conical form and the upper portion thereof having a curved shape and a fan-case connected to 85 said curved portion, a fan in said case, a lamp in the conical portion, means for rotating the fan, a lever controlling said means, the free end of said lever extending down adjacent to the conical portion of the casing. 90

In witness whereof I have hereunto set my hand in presence of two witnesses.

PAUL SCHWIDEWSKI.
